R. LEHKÝ

CENTRIFUGAL MACHINE

Filed May 13, 1926

FIG. 1.

FIG. 2.

RICHARD LEHKÝ
Inventor

By *John* *Attorney* *Otto Munk*

UNITED STATES PATENT OFFICE.

RICARDO LEHKÝ, OF BUENOS AIRES, ARGENTINA.

CENTRIFUGAL MACHINE.

Application filed May 13, 1926. Serial No. 108,843.

This invention has reference to certain improvements which I have introduced into centrifugal machines, such as are now in use for the manufacture of "pile" sugar, these 5 improvements having for their object that of making more easy and rapid the operation of extracting the lumps of sugar.

In the centrifugation of "pile" sugar there is at present a difficulty and a considerable loss of time involved in having to loosen the moulds which divide up the lumps of sugar in order that they may be taken out easily.

Even after the removal of the moulds, the 15 lumps of sugar generally remain adhering to the sides of the drum, making the work of taking them out more difficult.

To overcome this difficulty, I have superposed a ring, which, by means of a special 20 mechanism is lifted at will on completion of the centrifugation, thus loosening the lumps of sugar and the moulds interposed between them.

The object of the present invention is 25 that of detaching the lumps of sugar from the interior walls of the drum by means of a superposed ring, which is lifted by means of a special mechanism, consisting of a combination of levers arranged radially, or 30 some other suitable arrangement, beneath the principal base of the centrifugals.

With the present invention the following 35 objects are attained:—

1st. The lifting of the superposed ring by means of a screw, thus producing a 40 smooth, secure lift, without jars.

2nd. The placing of the levers beneath the principal base, thus making possible the 45 perfect seating of the superposed ring on the upper part of the principal base, over the whole surface, making impossible the entry of the cooked mass between the two bottoms, and assuring perfect working and cleanliness of the joints of the mechanism.

3rd. The mechanism does away with the 50 useless work, the lifting of the superposed ring being accomplished in exact relationship to the movement of the activating screw.

4th. The bearing points of the movable pins which lift the superposed ring are placed at the extremity of the principal bases, exactly at the points where the lumps 55 of sugar offer resistance.

For the better understanding of this de-

scription, I attach detailed sketch plans, in which:

Fig. 1, shows a plan of a centrifugal apparatus for the manufacture of "pile" sugar, improved by means of my invention. 60

Fig. 2, is an elevation of the same, projected in central vertical section.

Referring to the drawings A is the screw which works in the upper extremity of the axle B, and has a part of its head let into the thimble C, to which is joined the bell-shaped cover D. This screw secures at will the axial displacement of the flange E conjointly with the vertical arms F, suitably affixed to same. 70

These arms exert pressure upon the raised extremity of their respective levers G, which oscillate on the fulcrums H and which, have for their object the lifting of the pins I. The pins I, passing through the principal 75 base J, cause the lifting of the ring K, which is superposed on the said base.

The working is as follows:

When the usual period of centrifugation is completed, the screw A is turned, by 80 means of a key, and moved so that it descends. By this movement, the parts C, D, E, and the arms F are forced to descend. The lower extremities of the arms F, each press upon its respective lever G, which, 85 being balanced upon the pins or fulcrums H, suitably secured to the lower wall of the principal base, cause the other extremity to lift the pins I, which in turn lift the ring K. 90

By this simple operation, the easy and rapid removal and detachment of the lumps of sugar from the walls of the drum is obtained.

The elements described may vary in their 95 constructional form according to the capacity and construction of the centrifugals to which are to be applied the improvements which are the object of this application.

The nature of my invention having been 100 described and specified, with the method of putting it into practice, that which I claim as my exclusive property and invention is:

1. In a centrifugal machine used in the 105 manufacture of pile sugar, the combination with a centrifugally operated receptacle and an upright axle therefor, of a ring superposed on the bottom of the receptacle, and means operating to raise the ring off of the 110

said bottom comprising a plurality of pins operating under the ring, pivoted radial levers actuating said pins to move them axially thereof, and means adjustable from the upper elevation of the axle and operating to rock the levers to lift the pins.

2. In a centrifugal machine used in the manufacture of pile sugar, the combination with a centrifugally operated receptacle and an upright axle therefor, of a ring superposed on the bottom of the receptacle, means operating from below the said bottom to raise the ring above the elevation of the bottom, and means adjustable in the upper elevation of the axle and operatively associated with the first means to cause the latter to lift said ring.

3. In a centrifugal machine used in the manufacture of pile sugar, the combination with a centrifugally operated receptacle and an upright axle therefor, of a ring superposed on the bottom of the receptacle, pins disposed in said bottom and arranged to underlie the ring at spaced intervals, pivoted radially arranged levers operating under the bottom of the receptacle and disposed to en-

gage the pins, a plurality of upright members operating axially of the axle and arranged circumferentially about the latter, and means adjustable axially of the upper elevation of said axle and operating to simultaneously rock the levers to elevate the pins and ring.

4. A centrifugal machine of the character described in claim 3, in which the last named means comprises a screw adjustable in the upper end of said axle, a thimble supported by the screw and having a flange to which the upper ends of the upright members are attached.

5. A centrifugal machine of the character described, in claim 3, in which the last named means comprises a screw adjustable in the upper end of said axle, a thimble supported by the screw and having a flange to which the upper ends of the upright members are attached, and covering members carried by the thimble and disposed over the latter and connection of the members and flange.

RICARDO LEHKÝ.
